UNITED STATES PATENT OFFICE.

WILLIAM BRODHAGE, OF ST. LOUIS, MISSOURI.

GRAIN-CAR DOOR.

1,107,752.

Specification of Letters Patent. Patented Aug. 18, 1914.

Application filed March 13, 1913. Serial No. 754,113.

to all whom it may concern:

Be it known that I, WILLIAM BRODHAGE, citizen of the United States, residing at St. Louis, in the State of Missouri, have invented certain new and useful Improvements in Grain-Car Doors, of which the following is a specification.

This invention relates to grain car doors, and has for its object the provision of a closure for the door opening by the use of which grain will be effectually prevented from leaking through the opening and which will be so constructed and arranged that the full extent of the door opening may be utilized when it is desired to quickly unload the car.

Another object of the invention is to provide a grain car door which will, in both its opened and closed positions lie close to the side of the car and will not project into the same.

A further object of the invention is to provide a car door of such construction that it may be readily opened and in the act of opening will move away from the car body that portion of the grain lying against the same so that none of the grain will lodge behind the door and be lost.

Other incidental objects of the invention will appear as the description of the same progresses, and the invention consists in certain novel features which will be hereinafter first fully described and then more particularly pointed out in the appended claims.

In the annexed drawings, which fully illustrate the invention: Figure 1 is a side view of my improved door showing it in its closed position in full lines and partly opened in dotted lines; Fig. 2 is a horizontal section on the line 2—2 of Fig. 1; Fig. 3 is an elevation showing the door fully opened and showing the central door post removed from the door opening; Fig. 4 is a vertical transverse section taken through the central removable door post; Fig. 5 is an elevation showing the outer side of the door; Fig. 6 is a detailed perspective view of an internal brace employed within the door; Fig. 7 is a detail perspective view of the latch; Fig. 8 is a detail perspective view of the lower end of the removable post.

In carrying out my invention, I provide at each side of the door opening, upon the inner wall of the car, a T-shaped frame consisting of a vertical brace 1 secured at its upper end to the side door post 2 and at its

lower end to the floor of the car, as shown at 3. The upper end of the bracket or brace 1 is spaced from the door post, as shown at 4, and to the said brace, at the center of the same, I secure the longitudinally extending horizontal bar 5 which has its inner end secured to the side of the car, as shown at 6. Inserted through the upright brace 1 and the door post, near the lower ends thereof, is a bolt or similar device 7 constituting a pivot about which the door body 8 may swing.

It will be readily noted from the drawings that the structure thus far described is duplicated at the two sides of the door opening and it will be evident that the door bodies swing toward each other to extend across and close the door opening and swing away from each other to uncover the door opening, and, in the opened position, are retained between the side of the car and the bars 5. Each door member is preferably composed of a double series of boards fitted together and having interposed between them a metallic brace bar 9, the said brace bar being shown in detail in Fig. 6 and being provided at one end with an eye 10 adapted to fit around the pivot bolt or pin 7 and provided at intervals throughout its length with perforations 11 through which and the boards 12 of the door bodies fastening screws, rivets, or other devices may be inserted. The inner and outer faces of the door bodies are covered with sheet metal, as shown at 13, so as to reinforce the same and resist wear and the inner edges of the doors which are upright in the closed position thereof are beveled, as shown at 14, so that, as the door is opened, this beveled edge will take into the grain resting against the side of the car body and shove the same aside so that no portion of the grain will lodge between the door and the side of the car and be lost. At the lower inner corner of the door body, an enlargement or lug 15 is provided to reinforce the same around the pivot bolt or pin.

The described construction is preferred for economical reasons, but it will be understood that the door may be constructed entirely of metal if desired. The meeting edges of the door bodies are constructed with shoulders 16 adapted to overlap and interengage so that when the doors are in the closed position leakage of the grain between the door members will be positively prevented. In their outer faces, adjacent their outer lower corners, the door bodies are pro-

vided with notches or recesses 17 in which may be engaged the end of a convenient bar or other tool so that the door may be pried open against the pressure of the grain when it is desired to remove the contents of the car.

To hold the door members in the closed position against the outward pressure of the grain, I provide the central door post 18 which is adapted to be held in an upright position at the center of the door opening and at the outer side of the door members. This removable post is a stout wooden body preferably reinforced on its outer side with a metallic sheathing, indicated at 19, and the lower end of this sheathing is doubled upon itself beneath the lower end of the body of the post, as shown at 20, and has its extremity 21 tapered so that it may readily enter the space left between the sill 22 and a metallic plate or bar secured upon the upper surface of the same. In the drawing, the metallic plate 23 is shown as spaced from the sill by two lower plates interposed between the plate 23 and the sill and having their inner ends spaced apart, but this particular construction is not essential and the keeper to be engaged by the tapered extremity or hook 21 of the reinforcing plate 19 may be provided in any other convenient or preferred manner. The upper end of the reinforcing plate 19 is formed with an eye 24 which engages a bar 25 disposed horizontally upon the inner side of the car body and secured to the car body so as to extend from a point centrally over the door opening to a point beyond one side of the said opening, it being understood that the post is hung upon this bar 25 before the bar is secured in place. The end of the bar immediately over the door opening is bent downwardly and then upwardly to constitute a hook or hanger 26 having a flat side 27 through which a screw or other fastening device may be inserted into the body of the car. The post is provided on its sides, near its lower end with lateral enlargements or projections 28, one of which is provided with an eye or hook 29 adapted to engage over a pin 30 on the inner side of the car body when the post is removed from the door opening, as shown in Fig. 3.

Upon the sides of the post and above the center of the same are pivoted hooks or latches 31 which have inwardly projecting arms 32 provided with lugs 33 adapted to engage over the upper edges of the door members and rest on said edges so as to hold the doors in the closed position. The upwardly extending arms of the latches are provided at their upper ends with resilient fingers 34 provided with perforations adapted to engage pins 35 on the post so as to hold the latches in engagement with the door mem- 65 bars.

It is thought the operation and advantages of my improved grain car door will be readily understood from the foregoing description, taken in connection with the accompanying drawings.

When the car is to be loaded and the grain retained within the car, the post 18 is brought into a vertical position at the center of the door opening with the hook 21 at its lower end engaging under the keeper or plate 23 and the doors are then moved to closed position so as to extend across the door opening and bear against the inner face of the post. The latches 31 are then engaged over the upper edges of the doors and the grain then fed into the car through the space between the upper edges of the door members and the top of the door opening. When the car is to be unloaded, a lever is engaged in each recess 17 and the door then pried upwardly so as to assume the position shown in dotted lines in Fig. 1. The grain will then escape below the lower edges of the door openings and the lower corners of the doors will be supported by the enlargements 28 on the post until the pressure of the grain has been reduced sufficiently to permit the doors to easily swing clear of the door opening. As the doors move inwardly, the beveled edges thereof will push the grain away from the side of the car, as before stated, and the doors may move over so as to rest upon the floor of the car behind the frame composed of the bar 5 and the upright 1, as will be readily understood. If it should now be desired to rapidly discharge the grain from the car, the lower end of the post is disengaged from the keeper or plate 23 and the post then swung upwardly and laterally upon its connection with the hook 26 and bar 25 and then slid to one side of the door opening and supported upon the said bar and the support 30, as shown in Fig. 3. The bar will thus be out of the way so that the operation of unloading the car will not be hampered.

It will be readily seen that I have provided a grain car door which will be very strong and durable and which may be easily operated to retain grain within the car or permit the unloading of the car as may be desired. The several parts of the device are all simple in construction so that the door may be applied to any car at a slight expense.

What I claim is:—

1. The combination with a car body having a door opening therein, of a hanger bar secured to the car body above the said opening and extending from a point centrally over the opening to a point beyond the side thereof, a post slidably and pivotally fitted upon said bar and adapted to extend vertically across the door opening, means for supporting said post above and at one side

of the opening, and door members pivotally mounted at the sides of the opening and adapted to extend over the same and bear against the said post.

5. 2. The combination with a car body having a door opening therein, of a keeper at the lower side of the said opening, and a post movably hung upon the car body above the said opening and provided at its lower 10 end with means for engaging under said keeper.

3. The combination with a car body having a door opening therein, of a post movably hung upon the body above the door 15 opening and provided with a retaining device at its lower end, door members pivoted at the sides of the door opening and adapted to extend over the same, lateral enlargements on the sides of said post above the 20 lower end thereof against which the door members will rest when partly opened, a support upon the car body above and at one

side of the door opening, and means on one of the said lateral enlargements to engage said support. 25

4. The combination with a car body having a door opening therein, of a keeper on the car body at the lower side of the door opening, a post hung upon the car body above the door opening, a sheathing on said post having its lower end extended under and doubled on itself beneath, the lower end of the post to form a hook adapted to engage under said keeper, and door members pivotally mounted at the sides of the 30 door opening and adapted to extend across the same and rest against said post. 35

In testimony whereof I affix my signature in presence of two witnesses.
